UNITED STATES PATENT OFFICE.

WILLIAM A. SCHRAUBSTADTER, OF ST. LOUIS, MISSOURI, ASSIGNOR TO
INLAND TYPE FOUNDRY, OF ST. LOUIS, MISSOURI, A CORPORATION OF MISSOURI.

DESIGN FOR A FONT OF TYPE.

No. 37,594.

Specification for Design.

Patented Oct. 24, 1905.

Application filed May 17, 1905. Serial No. 260,903. Term of patent 7 years.

To all whom it may concern:

Be it known that I, WILLIAM A. SCHRAUBSTADTER, a citizen of the United States, and a resident of the city of St. Louis and State of Missouri, have invented a new, original, and ornamental Design for a Font of Type, of which the following is a specification.

My design consists in the features shown in the accompanying drawing, which forms part of this specification.

I claim—
The ornamental design for a font of type as shown.

W. A. SCHRAUBSTADTER.

In presence of—
FRED F. REISNER,
J. B. MEGOWN.
